DEVICE FOR DRYING PRINTS, PARTICULARLY COPPER PRINTS

Friedrich von Heinrich, Budapest, Hungary

Application September 9, 1936, Serial No. 100,024
In Austria September 14, 1935

5 Claims. (Cl. 34—12)

The present invention relates to drying devices for prints and particularly to devices of this type in which the freshly printed sheets are conveyed from the press to a drying chamber comprising an endless conveyor with supporting grids for the sheets. Upon entering the drying chamber, the sheets are transferred to the supporting grids which carry the sheets for a predetermined time through a dry hot atmosphere whereupon the dried sheets are discharged from the drying chamber.

One object of the present invention is to produce a drying apparatus of this type in which the drying process is highly intensified.

The second object is to produce a device in which the sheets are securely retained on the supporting grids.

Still another object of the present invention is to produce a drying device in which the distance of the individual supporting grids from one another is substantially reduced whereby the same output can be obtained with a drying chamber of substantially smaller dimensions.

Other objects will become apparent from the following detailed description of one embodiment of the invention illustratively exemplified in the accompanying drawing, in which

Fig. 1 shows the device in a vertical section, on a greatly reduced scale with only one group of conveying grids being represented;

Fig. 2 is a side view of one part of the conveyor device, on a less reduced scale; and

Fig. 3 shows a front view of two link elements with flat bars, grid rods and sheet retaining arms, on the original scale.

The freshly printed sheets, which leave for instance a copper plate press (not shown), fall onto a conveyor 1 (Fig. 1). This conveyor carries the individual sheets directly into the drying apparatus built into a heat insulated casing 2. The casing 2 contains the following constructional parts: two lateral supports, which in the elevation according to Fig. 1 are placed rearwardly of one another and for the sake of clearness are not shown; two horizontal shafts 3, 4 arranged one above the other and rotatably mounted in the supports; a conveyor 5 for the sheets to be dried, passing around said shafts; four fans 6 for maintaining the circulation of the hot drying air; and two sets of heating units 7. The finished dried prints are discharged from the drying chamber by means of a further conveyor 8, 9 and deposited in a box 10.

The conveyor 5 comprises four endless pairs of conveyor chains 16, 17, 18, 19 (Fig. 2), which are

horizontally arranged one inside the other and pass around the shafts 3, 4 (Fig. 1). The chains themselves consist of special link elements 10 (Fig. 3), into which flat iron bars 11 are firmly inserted, so that the oppositely disposed links 10 of each pair of chains carry a single bar. From the outer edge of each bar, there project outwardly firmly gripped rods 12, which form a kind of grid on each flat bar 11. At the lower and upper turning points of the chain the grids passing around these points separate radially from the adjacent grids.

The fresh prints pass individually from the conveyor 1 into the spaces between two adjacent grids at the lower turning point of the chain. Each grid picks up one paper sheet and carries it upwardly on the right strand of the chain. The fans 6 draw the air from the space 13 between the two strands of the chains, whereby the air withdrawn is replaced by fresh air passing through the interstices between the flat bars 11. The fans 6 convey the air to the heater batteries 7. The air, after passing over the heater batteries, returns over the sheets on the grids through the interstices of the flat bars 11 and then repeats the above described continuous circulation.

When the sheets reach the upper turning point of the chain, they will already be sufficiently dry to turn over at this highest point without danger of becoming damaged and each sheet falls onto the preceding grid with its printed side downwards. In order to prevent the sheets at the upper turning point from falling between the bars 11, appropriately bent wire arms 14 (Fig. 3) are provided on the flat bars 11 of the grids at a plurality of places, which arms 14 being bent perpendicularly to the planes of the grids, overlap the space between the grids.

In the descending left strand of the conveyor 5 (Fig. 1) a further drying of the prints and especially of the color takes place. The finished dried prints, on the side of the lower turning point opposite to the feed side, fall on to the conveyor 8, 9 and are stacked as already mentioned.

As may be seen in Fig. 3, the distance *a* between any two consecutive grids 12 carried by a single pair of chains, cannot, for reasons of stability, etc., be reduced to less than several centimetres. In the embodiment of the invention shown in the drawing, however, this distance is divided into four equal parts, for which purpose the pairs of chains 16 to 19 (Fig. 2) are staggered relative to one another in the direction of their movement to the extent of one quarter of the

distance *a*. The dividing grids 12 are shown schematically in dot and dash line in Fig. 3. In the example shown the space between two neighbouring rods 12 is 3 mm., while the gauge of the grid wires amounts to 4 mm. Hence the drying chamber can be better utilized and a greater number of printed sheets can be dried in a given time.

Having now particularly described and ascertained the nature of my said invention, and in what manner the same is to be performed, I declare that what I claim is:—

1. A device for drying printed paper sheets, comprising a housing provided with openings in the lower portions of two opposite walls for the introduction of the wet sheets and the removal of the dry sheets, a vertical conveyor in said housing including an endless conveyor chain having radially projecting grids adapted to receive and to carry the paper sheets, means to conduct hot air from both sides in substantially horizontal paths to the outer edges of said grids, and suction means between the two sides of said conveyor chain, to give a relatively high speed to the hot air striking the paper sheets on said grids.
2. A device for drying printed paper sheets, comprising a housing provided with openings in the lower portions of two opposite walls for the introduction of the wet sheets and the removal of the dry sheets, a vertical conveyor in said housing, said conveyor including a pair of parallel conveyor chains spaced from each other, horizontal bars connecting the corresponding links of both chains, each of said bars having a plurality of parallel radially projecting rods forming grids to receive and to carry the paper sheets,

means to conduct hot air from both sides in substantially horizontal paths to the outer edges of said grids and suction means between the two sides of said conveyor chain to give a relatively high speed to the hot air striking the paper sheets on said grids. 5

3. A device, as claimed in claim 2, in which said means to conduct hot air to the outer edges of said grids includes radiators arranged in said housing on both sides of the conveyor adjacent the free edges of the grids and conductors leading the air to be heated to said radiators. 10

4. A device, as claimed in claim 2, comprising further arms projecting radially from said horizontal bars intermediary said grid rods, said arms being bent at a right angle to overlap the distances between consecutive grids and to prevent the paper sheets from being sucked inwardly beyond said horizontal bars. 15

5. A device for drying printed paper sheets, comprising a conveyor including a pair of parallel conveyor chains spaced from each other, horizontal bars, connecting the corresponding links of both chains and carrying radially projecting grids, said bars filling a fraction of the longitudinal space occupied by the corresponding links, at least one additional pair of chains arranged parallel to said first pair of chain and angularly staggered with respect to the latter by a fraction of one link, said additional chains having grid carrying horizontal bars, in the spaces between the horizontal bars of said first mentioned pair of chains. 20 25 30
